UNITED STATES PATENT OFFICE.

MAHLON LOOMIS, OF LYNCHBURG, VIRGINIA, ASSIGNOR TO CHARLES S. HORN, OF WILMINGTON, DELAWARE.

CUFF OR COLLAR FASTENING.

SPECIFICATION forming part of Letters Patent No. 250,268, dated November 29, 1881.

Application filed May 25, 1881. (Model.)

To all whom it may concern:

Be it known that I, MAHLON LOOMIS, of Lynchburg, in the county of Campbell and State of Virginia, have invented a new and useful Improvement in devices for Fastening and Adjusting Cuffs and Collars to Shirts, of which the following is a full, clear, and exact description, reference being had to the annexed drawings, forming part of this specification.

10 My invention consists in a strip of metal bent at each end in opposite directions to form spring-hooks, having the inner surfaces roughened or serrated and the curved portions corrugated, as hereinafter described.

15 In the accompanying drawings, Figure 1 is an edge or side view of the cuff-holder, and Fig. 2 a view showing the application of the holder to a cuff and wristband of a shirt.

20 To make the adjustable cuff-holder I use a thin strip of sheet-brass about six inches in length and one-fourth of an inch in width. This I bend twice upon itself in opposite directions at one-third of its length from each end, thus forming a double spring-clasp about two inches

25 in length. The outer sides of the curved portions are slightly corrugated, so as to hold the reversed ends in close contact with the body of the clasp, and the inner or contact surfaces of the ends and body are roughened or serrated, in order that the cuff and wristband, when inserted between said parts, may be securely held in position. The clasp C being thus constructed, the wristband B is inserted into one of the open ends thereof, the jaw of

30 the clasp being slightly depressed to facilitate the entrance of the said band, and the cuff A is then put upon the wrist and a portion of it placed in engagement with the opposite end of the clasp in the same manner.

With this device the cuff may be worn without being buttoned to the shirt; but a still greater advantage is that it allows of easy and instantaneous adjustment of the cuff to any position required, for giving more or less margin below the coat-sleeve. If a shirt-sleeve 45 happen to be a little too long or too short, by the use of this adjustable fastener the cuff may at once be adjusted to its proper dress position.

In stating, as I have done, that I make this holder of brass and of certain dimensions I 50 do not wish to be understood as restricting myself as to material or size in its construction, for it may be made of wood, celluloid, ivory, or other substances. It may also be made larger or smaller and of one or more pieces, plain, corrugated, or ornamented with various jewels or devices; and whereas I plate the article with nickel it may be plated with any other desirable coating. It may also be made of wire instead of strip metal. The same device made 60 in the same manner, only about one inch in length, may be used to hold the shirt-collar to its proper position at the back of the neck.

Having thus described my invention, I claim as new and desire to secure by Letters Patent— 65 A device for attaching cuffs and collars to shirts, consisting of a suitable strip of metal bent at each end in opposite directions to form spring-hooks having their inner surfaces roughened or serrated, substantially as and for the 70 purpose specified.

MAHLON LOOMIS.

In presence of—

THOMAS R. LALLY,
JOS. NESTER.
